United States Patent

Des. 241,498
Patented Sept. 21, 1976

241,498

SCRAPER

Lloyd T. Smith, Newton, Kans., assignor to S/V Tool
Company, Inc., Newton, Kans.

Filed Sept. 12, 1975, Ser. No. 612,694

Term of patent 14 years

Int. Cl. D7—05

U.S. CL. D7—184

FIG. 1 is a top perspective view of a scraper showing my new design;

FIG. 2 is a top plan view thereof;

FIG. 3 is a side elevational view thereof;

FIG. 4 is a bottom view thereof;

FIG. 5 is a view showing one end thereof; and

FIG. 6 is a view showing the opposite end thereof.

The side of the scraper which is not shown is a mirror image of the side disclosed in FIG. 3.

I claim:

The ornamental design for a scraper, as shown and described.
